FOUNDATION GARMENT

Mack Kahn, Cedarhurst, N. Y.

Application March 30, 1955, Serial No. 35,280

Term of patent 7 years

(Cl. D20—2)

FIG. 1.

FIG. 2.

FIG. 3.

Fig. 1 is a front perspective view of the foundation garment, showing my new design;

Fig. 2 is a rear perspective view thereof, and
Fig. 3 is a side elevational view thereof.

I claim:

The ornamental design for a foundation garment, substantially as shown.
